FLASHLIGHT

Orville T. Wood, Clinton, Mass., assignor to Blake Manufacturing Corporation, Clinton, Mass., a corporation of Massachusetts

Application January 7, 1942, Serial No. 425,848

7 Claims. (Cl. 240—10.6)

This invention relates to flashlights and more particularly to flashlights of the kind in which the source of electrical energy, in the form of a battery of electrolytic cells, disposed within a casing, is in an electrical circuit including an incandescent lamp controlled by a circuit closer accessible from the exterior.

One object of the invention is the support and disposition of all the elements of the flashlight whereby various forms and shapes of casings may be utilized with the same assembly of battery, circuit closer, lamp and light directing medium.

Another object of the invention is a hand lamp construction in which all of the parts of the flashlight circuit are mounted on a chassis whereby they may all be removed from the casing as a unit for ready access and removal and replacement of parts.

It is also an object of the invention to provide a flashlight of the character described which permits of the use of any design of flashlight casing with a standard chassis.

A further object of the present invention is to provide a flashlight of the character indicated in which the cells are readily accessible for replacement.

Still another object of the invention is a chassis on which substantially all of the operative parts of the flashlight may be mounted and which at the same time permits the replacement of the batteries without disassembly of the casing and chassis as a whole.

It is also an object of the invention to provide a construction in which the support for the cells, lamp and reflector together with the electrical connections, including the circuit closer, may be assembled and inserted as a unit in the casing. To this end, these parts are mounted upon a base and the assembly so mounted is readily associated with the casing and removably secured in position.

Yet another object of the invention is a disposition of the active parts of the flashlight on a base or chassis capable of so being positioned that it may be used with any design of flashlight casing.

The invention also seeks a flashlight or hand lantern which is practical from the standpoint of ease and cheapness of manufacture and convenience and durability in use.

In carrying these aspects of the invention into effect, the incandescent lamp, reflector, battery, circuit closer and, if desired, the lens, are carried upon a base or chassis which forms one wall portion of the flashlight casing and which is removable in whole and in part from the casing. The casing may, in one modification, be formed with an aperture, closed by a lens, if desired, through which the light may be directed, while in another modification of the invention, the

chassis may be formed with an aperture closed by a lens, if desired, through which the light is directed.

These and other objects of the invention and the means for their attainment will be more apparent from the following detailed description, taken in connection with the accompanying drawings illustrating one embodiment by which the invention may be realized, and in which:

10. Figure 1 is a view, partly in section and partly in elevation, showing one modification of the flashlight of this invention, the view being taken on the line 1—1 of Figure 2;

Figure 2 is a view looking from the left in Figure 1;

Figure 3 is a transverse, sectional view taken in the plane indicated by the line 3—3 of Figure 2 and looking in the direction of the arrows;

Figure 4 is a view similar to Figure 1 but showing a modification of the invention; and

Figure 5 is a fragmentary view looking from the left in Figure 4.

Referring first to Figures 1 and 2, the flashlight is there illustrated as comprising a composite chassis comprising the elements 26, 28, 34, hereinafter described, which are collectively of generally elongated and irregular rectangular configuration over which the edge 12 of a three-sided generally trough shaped casing member 14 fits. In Figure 3, the casing member 14 is shown as substantially U-shaped in cross-section and progressively varying in cross-sectional proportions from one end to the other. In the Figure 1 modification, the casing is shown as having at its front end an opening 18, here shown as round, through which the light reflected from the lamp 20 passes. Obviously, the casing 14 may have any desired cross-sectional shape.

40 The sides of the casing are formed interiorly with lugs 22 which are tapped to receive screws 24 retaining the chassis or base plate on which all of the operative parts of the flashlight may conveniently be supported. Obviously other releasable devices may be resorted to in lieu of the fastening means 22, 24. Thus, since all operative parts of the flashlight can, if desired, be mounted on the chassis, the casing may assume any desired and ornamental shape.

50 The chassis is illustrated as comprising an irregularly shaped fixed front portion 26 preferably, but not necessarily, of sheet metal, which is held to the lugs 22 by the uppermost six screws 24 (Figure 1) and which chassis portion is shown as extending for about one-half the length of the casing.

An intermediate closure member or trap-door 28 closes, substantially, the other half of the casing and is secured to the said fixed front portion 26 by means of hinge 30 and is resiliently urged

toward its closed position by the coil spring 32 disposed at the hinged joint.

At the rear end of the flashlight, a fixed latch-carrying rear chassis portion 34 is also secured as by screws 24 to lugs on the casing and is provided with a slide or latch consisting of a rectangular latch plate 36 slidable on the last named fixed chassis member 34 and having a lip or end portion 38 which overlies (as viewed in Fig. 2) the under surface of the hinged door portion 28 of the chassis to retain the hinged closure member 28 in position. The slide is formed with a slot 42 receiving a pair of studs or rivets 40 and is thus reciprocable on the fixed portion 34 between positions retaining and releasing the trap-door 28.

The studs 40 may also retain the base portion 44 of a resilient battery positioning member 44, 46, 48 illustrated as a conductive spring bent upwardly from the base portion, as at 46, and then reversely bent, as at 48, to yieldingly engage the bottom portion or rear end of the zinc cup or terminal shell 50 of the battery 52 to urge the battery toward the front end of the casing. Thus the rearmost cell, urged by the battery positioning contact 48, is in engagement with the forward cell, the central terminal 54 of which is, in turn, engaged by the upwardly extending conductive leaf spring portion 56 of an L-shaped conductive member 55, 56, the base member 55 whereof is fixed in position on a non-conductive or insulatory sheet 58 secured to the chassis. This sheet 58 is provided with a longitudinally extending slot 60 which is in register with a corresponding slot in the chassis. A thumb piece 66 on the insulatory slide is slidable on the outside or bottom surface of the chassis and has a portion 68 extending inwardly through the slots in the chassis and non-conductive element 58 and carries, on its inner side, in sliding and conductive engagement with the portion 55, a contact member 70 movable by the thumb piece into engagement with the conductive strip 74. As shown, the contact 70 is formed with an upwardly bent resilient end 72, conveniently curved, to yieldingly engage, in its forward position, a contact strip 74 also mounted on the insulatory member 58 and adapted to be electrically engaged with the central terminal 76 of the lamp 20.

The lamp is threaded into a conductive socket 78 carried by a conductive support 80 mounted upon and in electrical connection with the metallic chassis or a conductive part thereof which, in turn, is in electrical connection with the zinc terminal 50 of the battery through the rear positioning spring 44, 48. Thus, when the slide 66 is advanced toward the forward end of the flashlight, an electrical connection is made with the central terminal 54 of the battery by means of the insulated contact 56, and, through the contact 70 and strip 74 with the central terminal 76 of the lamp base to illuminate the lamp 20. The lamp socket 78 forms the other terminal in contact with the lamp and is electrically connected with the metallic chassis. Thus, when a lamp is in position in the socket, the circuit is completed from the socket 78 through the conductive member 80 to the chassis and from the chassis through the positioning spring 44-48 to the zinc terminal 50 of the battery. The circuit is completed from the central terminal 54 of the battery through the spring contact 56, the sliding circuit closer 70-72 to the resilient con-

tact 74 making connection with the central terminal 76 of the lamp.

In the Figure 1 modification, there is formed an opening 18, for the light rays, in the end of the flashlight casing. A lens 82 is removably mounted, by a bezel 88, on a reflector 84 which is formed centrally with an aperture 86 adapted to register with the lamp socket but spaced therefrom to be out of electric connection therewith. The reflector 84 and its associated lens 82 are conveniently supported, as by mounting the reflector upon a non-conductive support 90 immediately behind the aperture 18 on the front end of the chassis portion 26.

In Figures 4 and 5, there is shown a modification of the flashlight of Figures 1 and 2 to illustrate the wide applicability of the invention to different situations and for different purposes. Here the casing 114 is not formed with the opening for the passage of light from the lamp, but is closed on all sides. It is formed with a continuous rim 112 adapted to fit down over the chassis 126, 128, 134 which is substantially identical with the chassis described in respect of Figures 1 and 2. Many of the parts of this flashlight are similar to that of Figures 1 and 2 and like reference characters are affixed to corresponding parts. In this instance, however, the chassis portion 126 is formed with an opening 94, shown as circular, upon the edges of which rest a lens 96. The lens is held in closing relation to the opening 94 by an outwardly offset rim portion 98 of a reflector 100, which may be removably secured as by screws 102 passing through apertures in a flange 104 on the rim 98. Obviously, other releasable fastening means may be used. The reflector 100 is formed integral with a lamp socket 106 receiving the lamp 20 so that the lamp base is in electrical connection with the chassis through the reflector 100, rim 104 thereof and, through the chassis, with the zinc cup terminal 50 of the battery, as before. If the chassis is not conductive, a conductive strip for this purpose may be carried by the chassis.

The circuit closer 170 on the slide 66 has an angularly bent resilient end 108 which engages a contact strip 174 adapted to be engaged by the central terminal 76 of the lamp. As before, the contact strip 174 is insulated from the conductive chassis by the insulatory sheet 58. Circuit closer member 170 is in electrical engagement with a fixed L-shaped contact 156 against which the terminal 54 of the dry cell abuts.

It will be obvious in respect of both of the modifications discussed herein that the chassis may be composed of insulatory material and that a conductive strip extending along the chassis may be utilized to complete the circuit between the lamp contacts and the battery contacts.

The chassis of either modification of this invention is capable of use with casings of various shapes and compositions and while illustrated as non-conductive, the casing may obviously be formed of a conductive material so long as suitable insulating material is utilized to insulate the same from the conductive chassis and the battery.

It will thus be seen that a flashlight is provided all of the operative parts of which are mounted upon a chassis or removable side or bottom of the flashlight. The flashlight body member is thus permitted to assume various shapes and forms both utilitarian and ornamental and may be readily released and removed

from the chassis to permit replacement of lamp bulbs, batteries or repairs, while, for the simple manipulation of replacing a battery, a "trap-door" in the chassis may be released and opened to allow the batteries to be withdrawn and new batteries inserted merely by the manipulation of a releasable latch.

Various modifications will occur to those skilled in the art in the composition, configuration and disposition of the component elements going to make up the invention as a whole and no limitation is intended by the phraseology of the foregoing description or illustrations in the accompanying drawings except as indicated in the appended claims.

What is claimed is:

1. In a flashlight, in combination, a flat plate-like composite chassis, a trough-shaped casing having a peripheral edge lying in a common plane and of proportions and dimensions commensurate with the composite chassis, said chassis having all operative elements of a flashlight including a light, reflector and circuit closer mounted thereon, said casing and said chassis being provided with coacting securing means whereby said composite chassis may interchangeably receive any trough-shaped casing having the said commensurate dimensions and proportions, said composite chassis comprising sections secured to said casing in spaced relation and defining between them an opening for insertion of battery cells, and a closure adapted to be secured across said opening.

2. In a flashlight, in combination, a flat plate-like composite chassis, a trough-shaped casing having a peripheral edge lying in a common plane and of proportions and dimensions commensurate with the composite chassis, said chassis having all operative elements of a flashlight including a light, reflector and circuit closer mounted thereon, said casing and said chassis being provided with coacting securing means whereby said composite chassis may interchangeably receive any trough-shaped casing having the said commensurate dimensions and proportions, said composite chassis comprising sections secured to said casing in spaced relation and defining between them an opening for insertion of battery cells, a closure for the opening carried by one of said sections, and latching means for the closure carried by the other of said sections.

3. In a flashlight, in combination, a flat plate-like composite chassis, a trough-shaped casing having a peripheral edge lying in a common plane and of proportions and dimensions commensurate with the composite chassis, said chassis having all operative elements of a flashlight including a lens, reflector and circuit closer mounted thereon and having an opening for the passage of light in alignment with said lens, said casing and said chassis being provided with coacting securing means whereby said composite chassis may interchangeably receive any trough-shaped casing having the said commensurate dimensions and proportions, said composite chassis comprising sections secured to said casing in spaced relation and defining between them an opening for insertion of dry cells, and a closure adapted to be secured across said opening.

4. In a flashlight, in combination, a flat plate-like composite chassis, a trough-shaped casing

having a peripheral edge lying in a common plane and of proportions and dimensions commensurate with the composite chassis and being formed with an opening for the passage of light, said chassis having all operative elements of a flashlight including a lens, reflector and circuit closer mounted thereon, said casing and said chassis being provided with coacting securing means whereby said composite chassis may interchangeably receive any trough-shaped casing having the said commensurate dimensions and proportions, said composite chassis comprising sections secured to said casing in spaced relation and defining between them an opening for insertion of dry cells, and a closure adapted to be secured across said opening.

5. In a flashlight, in combination, a flat plate-like composite chassis, a trough-shaped casing having a peripheral edge lying in a common plane and of proportions and dimensions commensurate with the composite chassis, said chassis having all operative elements of a flashlight including a lens, reflector and circuit closer mounted thereon, said casing and said chassis being provided with coacting securing means whereby said composite chassis may interchangeably receive any trough-shaped casing having the said commensurate dimensions and proportions, said composite chassis comprising sections secured to said casing in spaced relation and defining between them an opening for insertion of dry cells, and a closure adapted to be secured across said opening.

6. In a flashlight, in combination, a flat plate-like composite chassis of electrically conductive material, a trough-shaped casing having a peripheral edge lying in a common plane and of proportions and dimensions commensurate with the edges of said composite chassis, said chassis having all operative elements of a flashlight including a light, circuit closer and battery contacts mounted thereon, said conductive chassis forming a part of the electrical circuit between said operative elements, said casing and said chassis being provided with coacting securing means whereby various casings having the said commensurate dimensions and proportions may be interchangeably secured to said chassis, said composite chassis comprising sections secured to said casing in spaced relation and defining between them an opening for insertion of battery cells, and a closure adapted to be secured across said opening.

7. In a flashlight, in combination, a flat plate-like composite chassis, a trough-shaped casing having a peripheral edge of proportions and dimensions commensurate with the composite chassis and closely surrounding its periphery, said chassis having all operative elements of a flashlight including the light, circuit closer and battery contacts mounted thereon, said casing and said chassis being provided with coacting securing means comprising lugs internally of said casing adjacent its edge adapted to be engaged by fastening means associated with said composite chassis, said chassis comprising sections secured to said lugs in spaced relation and defining between them an opening for insertion of battery cells, and a closure adapted to be secured across said opening.

ORVILLE T. WOOD.
